RADIO RECEIVER

Rene A. Braden, Collingswood, N. J., assignor to
 Radio Corporation of America, a corporation of
 Delaware

Application December 1, 1933, Serial No. 700,472

9 Claims. (Cl. 250—20)

My invention relates to radio receivers and particularly to circuits and apparatus for providing an improved tuning control therefor.

An objectionable feature of present high quality radio receivers is that the selectivity has been increased to a point where they are somewhat difficult to tune. Furthermore, it is feasible, and desirable from many standpoints, to make the tuning of radio receivers still sharper, one way of accomplishing this being to utilize a sharply selective "background noise" suppressor circuit. It is impractical to do this, however, when employing the usual tuning control for the reason that such a receiver must be tuned very carefully in order to avoid tuning through the desired station.

It is, accordingly, an object of my invention to provide an improved tuning device for radio receivers.

More specifically, it is an object of my invention to provide automatic tuning control means which overcomes the above-mentioned objection to sharply tuned receivers.

A still further object of my invention is to provide a radio receiver which may be tuned exactly to an incoming signal without the aid of sight or hearing, and without preselecting the stations.

A still further object of my invention is to provide an improved magnetic clutch which may be utilized in my improved tuning apparatus.

In one embodiment of my invention, I couple the tuning knob or tuning control of a radio receiver to the rotor shaft of the tuning condensers through a clutch which preferably is magnetically operated. When tuning between stations, the clutch is energized whereby the capacity of the tuning condensers can be varied by rotating the tuning knob. The instant that the receiver is tuned to an incoming signal, the amplified signal energy operates a relay tube which de-energizes the clutch, thus disconnecting the tuning knob from the condenser shaft. Consequently, the tuning condensers stop exactly at the point where the receiver is tuned exactly to the incoming signal, and further accidental rotation of the tuning knob has no effect.

The clutch may be again energized and the receiver tuned to another station either by pushing in the tuning knob, in one embodiment of the invention, or by rotating the tuning knob a predetermined amount, in accordance with another embodiment of my invention.

Other objects, features and advantages of my invention will appear from the following de-

scription taken in connection with the accompanying drawings in which

Figure 1 is a circuit and schematic diagram of a radio receiver embodying my invention;

Fig. 1a is a set of curves showing certain characteristics of the circuit illustrated in Fig. 1;

Fig. 2 is a schematic diagram of another embodiment of my invention;

Fig. 3 is a view taken on the line 3—3 of Figure 2; and

Fig. 4 is an exploded view of a portion of the structure shown in Figs. 2 and 3.

Referring to Fig. 1, one embodiment of my invention is shown applied to a superheterodyne receiver. The receiver includes a radio frequency amplifier 1 having an input circuit which is coupled to an antenna 3 through a transformer 5, and having an output circuit coupled to a first detector 7 through a transformer 9.

The secondary windings of the transformers 5 and 9 have variable tuning condensers 11 and 13, respectively, connected thereacross in the usual manner, for selecting a desired incoming radio signal. An oscillator 15 is provided which is coupled to the first detector 7 for the purpose of heterodyning an incoming signal to produce an intermediate frequency signal in the output circuit of the first detector.

The frequency of the oscillator output may be varied by adjusting a variable condenser 17 which preferably, is one unit of a gang condenser including the tuning condensers 11 and 13, these three condensers being variable through a common control device as indicated by the dotted line 19.

The output of the first detector 7 is transferred to the input circuit of an intermediate frequency amplifier 21 through a tuned intermediate frequency transformer 23. The output of the intermediate frequency amplifier 21 is likewise transferred to the input circuit of the second detector 25 through a tuned intermediate frequency transformer 27, the second detector being a diode rectifier which is one unit of a diode-triode vacuum tube 29.

The tuned transformers 23 and 27 are band-pass filters which have a pass range of sufficient width to pass the intermediate frequency carrier and at least one signal side band.

The circuit of the second detector includes a resistor 31 across which the audio signal appears. This signal is impressed upon the control grid of an audio frequency amplifier tube 33 through a conductor 35.

The resistor 31 is shunted by an intermediate

frequency bypass condenser 31, whereby the intermediate frequency voltage output of amplifier 21 is impressed across the second detector or diode rectifier elements 39 and 41 through a low 5 impedance circuit.

In the preferred embodiment of the invention, both automatic volume control and noise suppressor circuits are included, which are utilized for increasing the selectivity of the receiver in 10 addition to performing their usual functions. The automatic volume control may be obtained by connecting the control grids of the amplifiers 1 and 21 and the first detector 7 to the negative or plate end of the resistor 31 through resistors 43, 15 45, and 47 individual to the control grids and through a common filter resistor 49.

A filter condenser 51 is connected between the grid end of the resistor 49 and ground, for preventing audio frequency or higher frequency voltage 20 variations from being impressed upon the control grids. Any increase in the strength of the carrier wave of a received signal will increase the voltage drop across the resistor 31 whereby the control grids of tubes 1, 7, and 21 will become 25 more negative to lower the gain in the tubes.

The noise suppressor circuit includes an intermediate frequency amplifier tube 53, a diode rectifier 55, and a control tube 57. The input circuit of the intermediate frequency amplifier tube 30 53 is coupled to the output circuit of the tuned intermediate frequency transformer 23 through a coupling condenser 59 and a coupling resistor 61.

Upon reception of a signal, the intermediate 35 frequency output of the amplifier tube 53 is transferred to the diode rectifier 55 through a transformer 63 sharply tuned to the intermediate frequency, whereby a voltage drop is produced along a resistor 65 in the diode rectifier circuit.

40 The cathodes 69 and 67 of the diode rectifier 55 and the control tube 57, respectively, are connected together through a conductor 71, whereby both cathodes are connected to one end of the resistor 65. The control grid 73 of the control 45 tube 57 is connected to the other end of the resistor 65, whereby the control grid, 73, will be made highly negative with respect to its cathode when current flows in the resistor 65.

The plate 75 of the control tube 57 is supplied 50 with positive potential from any suitable source, such as a battery 77. The negative terminal of the battery is connected to ground so that the plate circuit of the control tube 57 includes the biasing resistor 79 of the intermediate frequency 55 amplifier 21.

When there is no incoming signal, there is no voltage drop along the resistor 65 of the diode rectifier 55, and the grid 73 of the control tube 57 is at the same potential as its cathode 67. 60 Therefore, with no incoming signal, a current flow is maintained through the plate circuit of the control tube 57 which produces a voltage drop in the biasing resistor 79 of the intermediate frequency amplifier 21 sufficient to make amplifier 65 21 ineffective.

As soon as the variable condensers 11, 13, and 70 17 are tuned to the frequency of an incoming signal, the resulting current flow in the resistor 65 biases the control tube 57 to cut-off, and the noise suppressor current no longer flows through the biasing resistor 79 of amplifier 21. Thus, upon 75 reception of the signal, the receiver becomes operative to supply a signal to the loudspeaker.

In accordance with a specific embodiment of 75 my invention, the tuning knob 81 of the radio

receiver is coupled to the rotor shaft of the condensers 11, 13, and 17 through a magnetic clutch 85 which comprises a U shaped iron core 87 having a magnet coil 89 wound thereon. Two clutch plates 91 and 93 are provided, the plate 91 being fastened to one end of a shaft 95 rotatably mounted in one leg of the iron core. This shaft is connected to the rotor shaft of the gang condenser, as indicated by the dotted line 19. 10

The other clutch plate 93 is fastened to one end of another shaft 97 which is rotatably mounted in the other leg of the iron core.

The tuning knob 81 is provided with a sleeve 99 and is mounted upon one end of the shaft 15 97 in such a manner that it is axially movable with respect to the shaft, but not rotatably movable with respect thereto.

A flange 101 is provided on the tuning knob 20 sleeve 99 for cooperation with a switch 103. The switch 103 may be closed by pushing the tuning knob 81 in towards the panel indicated at 105, while the clutch shaft 97 may be rotated by the tuning knob when it is in any axial position.

The clutch plates 91 and 93 may comprise 25 flexible saucer-shaped discs of soft iron which are mounted so close together that when current flows through the magnet coil 89, they are pulled together by the magnetic flux passing through the iron core 87 and through the shafts 95 and 97, these shafts being made of magnetic material.

It will be apparent that when the magnetic coil 89 is energized, the radio receiver may be tuned by rotating the tuning knob 81, and that when 35 the magnetic coil 89 is de-energized, the setting of the tuning condensers 11, 13, and 17 cannot be changed by rotation of the tuning knob.

Referring now to the control circuit for the 40 magnetic coil 89, the triode portion of the diode-triode vacuum tube 29 functions as a control tube for the clutch 85. The control grid 107 of the tube 29 is connected to the negative end of the diode resistor 31 through a filter resistor 109. 45

The grid end of the filter resistor 109 has an alternating current connection to ground through a filter condenser 111. The filter, consisting of the resistor 109 and condenser 111, is provided for the purpose of preventing alternating voltage 50 fluctuations from being impressed upon the control grid 107.

The plate 113 of the vacuum tube 29 is supplied with positive potential from a suitable source such as a battery 115 having its negative 55 terminal connected to ground and its positive terminal connected to one end of the magnet coil 89. The other end of the magnet coil is connected to the plate 113 through a conductor 117. 60

It will be evident that when the receiver is not tuned to an incoming signal, there will be no voltage drop along the diode resistor 31, and the control grid 107 of the triode section will be at ground potential. Therefore, there will be a flow of current in the plate circuit of the triode section, this current flowing through the magnet coil 89 and energizing the clutch 85. Consequently, so long as no signal is being received, the receiver may be tuned by rotating the tuning knob 81. 70

As soon as the receiver is tuned to an incoming signal a voltage drop appears across the diode resistor 31, and the grid 107 is made sufficiently negative to block the tube, whereby the 75

magnetic clutch 85 is de-energized. As a result, the tuning condensers 11, 13, and 17 are disengaged from the tuning knob 81 so that they stop exactly at the point where the station is 5 tuned in, and further accidental rotation of the tuning knob does not detune the receiver.

It may be noted that the use of a sharply tuned circuit is important in obtaining proper operation of the clutch. This will be more readily 10 understood by referring to Fig. 1a where curve 120 is the resonance or selectivity curve of the noise suppressor, and brake circuit (determined primarily by tuned transformer 63), while curve 122 is the selectivity curve for the signal channel 15 (determined primarily by tuned transformers 23 and 27). By making the brake circuit much more sharply tuned than the signal channel, the brake is prevented from operating before the receiver is tuned to the carrier frequency 20 itself, that is, to the middle of the communication channel.

It will be understood that the rotors of the tuning condensers should be properly counterbalanced or provided with sufficient friction to 25 hold them in any position in which they are stopped.

When it is desired to tune away from a station, the tuning knob 81 is again connected to the tuning condensers through the clutch 85 by 30 pushing in on the tuning knob to close the switch 103. This causes current to flow from the battery 115 through the magnet coil 89, the resistor 119, and the switch 103 so that the clutch is 35 energized.

After the tuning knob has been pushed in and rotated far enough to tune out the station that was being received, the tuning knob is permitted to spring out away from the panel, whereby the switch 103 is opened and the receiver is in condition to stop automatically on the next station. The tuning knob is then rotated further until the receiver is tuned to the next station at which time the clutch is again automatically de-energized to stop the condensers at the correct position. 45

If it is desired to tune the receiver in the conventional manner, a switch 121 may be closed which causes the clutch 85 to remain energized at all times.

Referring to Fig. 2, there is shown a different mechanism for energizing the clutch when it is desired to tune away from a particular station. This mechanism is illustrated in connection with the same rectifier circuit shown in Fig. 1, the receiver being indicated schematically at 125. In the two figures, like parts are indicated by the same reference numerals.

In Fig. 2 the tuning knob 81 is shown rigidly connected to the clutch shaft 97. By means of 60 a mechanism indicated generally at 127, the clutch may be energized by rotating the tuning knob 81 through a predetermined number of degrees.

Referring to Figs. 2, 3, and 4, the mechanism 65 for obtaining this control comprises an arm 129 pivotally mounted at one end and connected at the other end to the iron core 131 of a solenoid 133. The arm 129 is provided with supporting members 132 in which a shaft 135 is mounted. 70 A gear wheel 137 is rotatably mounted upon the shaft and is positioned above a gear wheel 139 keyed to the clutch shaft 97.

A contact disc 141, having diametrically opposed contact pins 143 and 145, is rotatably 75 mounted upon the shaft 135 for the purpose of

actuating a clutch energizing switch 147. The position of the contact disc 141 may be controlled through the gear wheel 137 by means of two spiral springs 149 and 151.

The inner end of the spring 149 is mechanically connected to the gear wheel 137 through an arm 153, as indicated by the dotted line 155 in Fig. 4. The outer end of spring 149 is connected to the contact disc 141 through an arm 157, as indicated by the dotted line 159 (Fig. 4), whereby 10 rotation of the gear wheel 137 will rotate the contact disc.

There is also a connection between the contact disc 141 and the outer end of the spring 151 through an arm 161, the inner end of this spring 15 being fastened to the supporting members 132 through an arm 163, these connections being indicated by the dotted lines 165 and 167, respectively, in Fig. 4. Since one end of the spring 151 is fastened to a fixed point, it opposes the rotation of disc 141. If the springs 149 and 151 are identical, as they preferably are, a half rotation 20 of the gear wheel 137 in either direction causes a quarter rotation of the disc 141. Assuming the gears 137 and 139 have a one to one 25 ratio, a half rotation of the tuning knob 81 likewise causes a quarter rotation of disc 141.

The magnet coil 169 of the solenoid 133 is connected in series with the magnet coil 89 of the clutch 85 so that when the clutch 85 is energized by plate current from the vacuum tube 29 the solenoid 133 is energized and the gear wheel 137 is pulled up out of contact with the lower gear wheel 139. It will be noted that at any time the receiver is not tuned in to an incoming signal, 30 the clutch 85 will be energized and the two gear wheels will be held out of engagement. 35

As soon as the receiver is tuned to an incoming signal by rotating the tuning knob 81, the vacuum tube 29 is blocked by the incoming signal and the clutch 85 is instantly de-energized to disconnect the tuning knob from the tuning condenser shaft, as described in connection with Fig. 1. In addition, the solenoid 133 is de-energized and the gear wheel 137 immediately drops into engagement 40 with the lower gear wheel 139. 45

From the foregoing description of the contact disc mechanism, it will be apparent that, if the operator turns the tuning knob 81 a slight amount after the clutch is de-energized, there 50 will be no change in the circuit conditions and the receiver will remain tuned in on the station just received.

If the operator desires to tune away from this particular station and tune in the next station, 55 the tuning knob 81 is rotated a predetermined amount, a half turn, in the embodiment illustrated, with the result that the contact disc is rotated sufficiently to force either the contact pin 143 or the pin 145 against a switch arm 171 60 and close the switch 147.

Current then flows from the battery 115, through the switch 147, and the resistor 119, and the clutch 85 is instantly energized. A further rotation of the tuning knob 81 rotates the tuning condensers 11, 13, and 17 and the receiver is tuned away from the station that was being received. This results in the blocking potential being removed from the grid of the vacuum tube 29, the clutch 85 is energized by the plate 65 current of the tube 29 and, at the same time, the solenoid 133 is energized to pull the gear wheel 137 out of engagement with the lower gear wheel 129. 70

As soon as the gear wheels are moved out of 75

engagement, the springs 149 and 151 cause the gear wheel 137 and the contact disc 141 to rotate back to their original positions and the switch 147 is opened. The circuit is now back to its original condition, and as soon as the tuning knob is further rotated to a point where the receiver is tuned to the next station, the clutch and solenoid windings 89 and 169 are again automatically de-energized.

10 It should be understood that the above-described mechanism may be adjusted to cause engagement of the clutch in response to any desired degree of rotation of the tuning knob. Such an adjustment may be made either by changing the 15 gear ratio of the gears 137 and 139, or by changing the positions of the contact pins 143 and 145.

15 It should also be understood that a reducing gear or some other slow-motion drive (not shown) is employed for coupling the clutch shaft 95 to the 20 tuning condensers 11, 13, and 17. Thus, a half turn of the tuning knob will cause only a slight rotation of the tuning condensers.

25 From the foregoing description, it will be seen that I have provided what may be referred to as an "automatic tuning" system which greatly increases the ease with which any radio receiver may be tuned and which makes it practical to increase the selectivity of radio receivers to a degree that would make them exceedingly difficult 30 to operate with a conventional tuning control.

35 While I have described only two embodiments of my invention it will be apparent that various other modifications may be made therein without departing from the spirit and scope thereof and I desire, therefore, that only such limitations shall be placed thereon as are necessitated by the prior art and are set forth in the appended claims.

I claim as my invention:

40 1. A radio receiver comprising a tunable circuit for selecting a carrier wave, said tunable circuit including a variable tuning unit, a manual tuning control device, a clutch for mechanically coupling said tuning unit and said tuning device, and means for disengaging said clutch in response to the selection and reception of a carrier wave by said tunable circuit.

45 2. A radio receiver comprising a tunable circuit for selecting a carrier wave, said tunable circuit including a variable tuning unit, a manual tuning control device, an electromagnetic clutch normally energized for mechanically coupling said tuning unit and said tuning device, and means for deenergizing and permitting disengagement of said clutch in response to the selection and reception 55 of a carrier wave by said tunable circuit.

50 3. A radio receiver comprising a tunable circuit for selecting a carrier wave, said tunable circuit including a variable tuning unit, a manual tuning control device, a clutch connecting said tuning unit and control device and being electrically operable, a control tube having an anode circuit energized to cause said clutch normally to engage, and means for applying to said control tube a biasing potential proportional to the strength 60 of a selected and received carrier wave for substantially deenergizing said anode circuit, thereby to release said clutch.

65 4. A radio receiver according to claim 1 characterized in that said tuning device is a manu-

ally operable tuning knob, and further characterized in that means is provided for selectively engaging said clutch by moving said tuning knob to a predetermined position after said clutch has been disengaged.

5 5. A radio receiver according to claim 1 characterized in that said tuning device is a manually operable tuning knob, and further characterized in that means is provided for selectively engaging said clutch by moving said knob axially after said clutch has been disengaged.

10 6. A radio receiver according to claim 1 characterized in that said tuning device is a manually operable tuning knob, and further characterized in that means is provided for selectively engaging said clutch by rotating said knob a predetermined number of degrees after said clutch has been disengaged.

15 7. In a radio receiver of the superheterodyne type, means for converting an incoming radio signal to an intermediate frequency signal having a predetermined frequency, said means including a variable tuning element, a clutch through which said element may be varied, a magnet coil for said clutch, a relay tube having an output circuit, said output circuit being connected to said magnet coil, whereby said clutch is engaged when said relay tube is energized, and means including a circuit tuned to said intermediate frequency for de-energizing said relay tube in response to the reception 30 of an incoming signal, whereby said clutch is disengaged.

20 8. A radio receiver comprising a tunable circuit for selecting a radio signal, said circuit including a variable tuning unit, a manually operable tuning knob, a clutch for mechanically coupling said tuning unit and said tuning knob, means for disengaging said clutch in response to the selection of a radio signal by said tunable circuit, and means including a switch for selectively engaging 35 said clutch, said last means including a rotatable element positioned to operate said switch when rotated a predetermined amount and a driving unit for mechanically coupling said rotatable element to said tuning knob whereby said rotatable element may be rotated by turning said tuning knob, and means for uncoupling said rotatable element and said tuning knob in response to the selection of a radio signal by said tunable circuit.

40 9. A radio receiver comprising a tunable circuit for selecting a radio signal, said circuit including a variable tuning unit, a manually operated tuning knob, a clutch for mechanically coupling said tuning unit and said tuning knob, means for disengaging said clutch in response to the selection 45 of a radio signal by said tunable circuit, means for engaging said clutch in response to the closing of a switch, a rotatable element positioned to close said switch when rotated a predetermined amount in either direction, means for mechanically coupling said rotatable element and said tuning knob, means for uncoupling said rotatable element and said tuning knob in response to the selection of a radio signal by said tunable circuit, and means for returning said rotatable element to its original position when said rotatable element and said tuning knob are uncoupled.

RENE A. BRADEN.
